UNITED STATES PATENT OFFICE.

JOHN LAWRIE, OF BROOKSTON, INDIANA, ASSIGNOR OF ONE-HALF TO JOHN W. HOLTZMAN, OF SAME PLACE.

PLOW ATTACHMENT.

SPECIFICATION forming part of Letters Patent No. 295,925, dated April 1, 1884.

Application filed August 18, 1883. (No model.)

To all whom it may concern:

Be it known that I, JOHN LAWRIE, a citizen of the United States, residing at Brookston, in the county of White and State of Indiana, have invented certain new and useful Improvements in Plow Attachments; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a vertical sectional view. Fig. 2 is a bottom plan view. Fig. 3 is a detail showing a front view of the plow-standard. Fig. 4 is a detail showing a rear view of the bracket, and Fig. 5 is a side view 20 of the same.

This invention relates to plows and scrapers, and is designed as an improvement on the shovel-plow granted to me by Letters Patent No. 261,001, dated July 11, 1882.

It consists in providing the lower end of the standard-sheth, in its front face, with a hexagonal matrix, and the tri-armed bracket with a hexagonal boss to fit the matrix, and securing the bracket to the standard-sheth by a bolt 25 and nut, so that either point or side of the plow or scraper may be made available by loosening the bolt, making the required shift, and again tightening the bolt, as will be hereinafter fully described, and particularly pointed out in the claims appended.

Referring by letter to the accompanying drawings, *a* designates the plow-point, which is nearly shield form in outline, is concave in its face, convex on its back or rear side, and 30 has cutting-edges between three equidistant points, *b* *b'* *b''*. The central portion of the plow point or blade is necessarily made heavier than the edges, in order to compensate for wear and to render the point durable. Three equidistant countersunk perforations, *c*, are made in the shovel or blade for the reception of the bolts *d*, by which the tri-armed bracket *e* is secured thereto. These arms *f* and *f'* are an-

gular, as shown, and rise from the convex face of the plow-point. The arm *f'* is shorter in 50 its vertical dimension than the other two, *f*, *f'*, for a purpose presently hereinafter explained. The face *g* of the bracket is centrally perforated at *h*, for the reception of a bolt, *i*, by which it is pivoted to the foot of 55 the standard-sheth or auxiliary standard *k*, as shown. The extremity of this foot is slightly enlarged at its front or face portion, and is provided with a hexagonal matrix, *l*, and a central perforation, *m*, for the bolt *i*. The tri- 60 armed bracket *e* is provided on the rear face of its central portion with a hexagonal boss, *n*, of a size to fit the matrix *l*, in which it rests when in place on the foot.

Taking the plow in the position it occupies 65 when used as a shovel-plow as the normal one, the adjustments will now be described. In the normal position the shorter arm, *f'*, of the bracket must be in a line vertical to and parallel with the standard, the bolt *i* locking it in 70 place. By loosening the bolt *i*, lifting the boss from its matrix, and turning the plow-point on its pivot toward the left hand until the side of the boss that has been in engagement with the top line of the matrix will engage the 75 next angle at that side, and then tightening the bolt, the plow will turn the furrow to the left. A reverse turn from the normal position will cause the furrow to be turned to the right. It will be observed that the boss can 80 be turned to the second side angles and to the bottom line of the matrix, so that there may be five adjustments from the normal position, to make a right-hand, center, or left-hand plow or scraper.

The device is quite simple in its construction, is easily adjusted, and is strong and durable.

Having thus fully described my invention, what I claim as new, and desire to secure by 90 Letters Patent, is—

1. The standard-sheth or auxiliary stand-ard *k*, provided in its front face, at its lower extremity, with the hexagonal matrix *l*, and the central perforation, *m*, from front to rear, 95 in combination with the tri-arm bracket *e*,

having the arms f and f' , the hexagonal boss n on the rear face of its central portion, and the central perforation, h , and the pivot-bolt and nut i , substantially as specified.

5 2. A plow-standard having a hexagonal matrix in its front face near its lower end, in combination with a tri-arm bracket having a central hexagonal boss to fit the matrix, and

a bolt and nut for connecting the two together, substantially as specified.

In testimony whereof I affix my signature in presence of two witnesses.

JOHN LAWRIE.
